CLAIM

We claim an ornamental design for a pair of earphones, as shown and described.

DESCRIPTION

FIG. 1 is a perspective view of one earphone of a pair of earphones showing the new design;

FIG. 2 is another perspective view of FIG. 1;

FIG. 3 is another perspective view of FIG. 1;

FIG. 4 is another perspective view of FIG. 1;

FIG. 5 is another perspective view of FIG. 1;

FIG. 6 is another perspective view of FIG. 1;

FIG. 7 is a front elevational view of FIG. 1;

FIG. 8 is a rear elevational view of FIG. 1;

FIG. 9 is a left side elevational view of FIG. 1;

FIG. 10 is a right side elevational view of FIG. 1;

FIG. 11 is a top plan view of FIG. 1;

FIG. 12 is a bottom plan view of FIG. 1; and,

FIG. 13 is a perspective view of the pair of earphones showing the new design, one earphone is a mirror image of the other.

The broken lines in the figures depict environment that forms no part of the claimed design.
